Primary Examiner—Alan P. Douglas*Assistant Examiner*—Jeffry H. Musgrove*Attorney, Agent, or Firm*—Stetina Brunda & Buyan**[57] CLAIM**

The ornamental design for a dust collection device for floor sander, as shown and described.

DESCRIPTION

FIG. 1 is a front perspective view of the dust collection device for floor sander of the present invention showing my new design, with the phantom lines depicting solely environmental structure and forming no part of the claimed design;

FIG. 2 is a large front perspective view thereof;

FIG. 3 is a rear perspective view thereof; and,

FIG. 4 is a bottom perspective view thereof.
